UNITED STATES PATENT OFFICE.

HENRY J. GROTH, OF LOS ANGELES, CALIFORNIA.

DESIGN FOR A FIREPLACE.

47,243.

Specification for Design.

Patented Apr. 20, 1915.

Application filed January 2, 1915. Serial No. 280. Term of patent 14 years.

To all whom it may concern:

Be it known that I, HENRY J. GROTH, a citizen of the United States, residing at Los Angeles, in the county of Los Angeles and State of California, have invented a new, original, and ornamental Design for Fireplaces, of which the following is a specification, reference being had to the accompanying drawing, forming part hereof.

Figure 1 is a front elevation of a fire place

embodying my new design. Fig. 2 is a fragmentary horizontal section on the line 2—2 of Fig. 1 and showing the indentations.

I claim:

The ornamental design for a fire place as shown.

HENRY J. GROTH.

Witnesses:

GRACE DODGE NAQUIN,
SEMER G. WELLS.
